CLAIM

The ornamental design for a grille surround for a vehicle, as shown and described.

DESCRIPTION

FIG. 1 is a perspective view taken from a front, left side of a grille surround for a vehicle, in accordance with our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the Figures, where shown: (i) the evenly-spaced dashed lines used in the drawings depict environmental structures that form no part of the claimed design; and (ii) the dotted/dashed lines define the boundaries of the design that also form no part of the claimed design.
